[57] CLAIM

The ornamental design for a combined hook and anchorage casing, as shown.

DESCRIPTION

FIG. 1 is a front perspective view of a combined hook and anchorage casing showing my new design;

FIG. 2 is a rear perspective view thereof on a reduced scale and with the hook in an alternate position;

FIG. 3 is a greatly enlarged top perspective view thereof;

FIG. 4 is a greatly enlarged bottom perspective view thereof with the hook and upper portion of the chain omitted for convenience of illustration;

FIG. 5 is an enlarged front perspective view illustrating the inside of the anchorage casing with the front wall removed and a portion of the chain and entire hook deleted for clarity of illustration;

FIG. 6 is a greatly enlarged front perspective view of the hook, it being understood that the chain and anchorage casing have been omitted for clarity of illustration; and

FIG. 7 is a rear perspective view of FIG. 5.

UNITED STATES PATENT OFFICE
CERTIFICATE OF CORRECTION

Patent No. Des. 249,019 Dated August 22, 1978

Inventor(s) Lars Fredriksson

It is certified that error appears in the above-identified patent and that said Letters Patent are hereby corrected as shown below:

In the Description:

Delete the description of FIG. 7 and substitute therefor -- FIG. 7 is a perspective view similar to FIG. 6 but taken from the rear of the hook; and

Fig. 8 is an enlarged elevational view of the interior of the front panel of the anchorage casing --.

In the Drawings:

Sheet 3: change "FIG. 6" to -- FIG. 8 --.

Signed and Sealed this

Tenth Day of July 1979
